UNITED STATES PATENT OFFICE.

FRANCIS M. WILTROUT, OF CORUNNA, INDIANA.

PORTABLE CONCRETE-TILE MOLD.

939,578.

Specification of Letters Patent.

Patented Nov. 9, 1909.

Application filed October 12, 1908. Serial No. 457,355.

To all whom it may concern:

Be it known that I, FRANCIS M. WILTROUT, a citizen of the United States, residing at Corunna, in the county of Dekalb 5 and State of Indiana, have invented a new and useful Portable Concrete-Tile Mold, of which the following is a specification.

This invention relates to portable tile making molds of that general class shown and 10 described in my former United States Letters Patent issued to me on the 24th day of April 1906, under No. 818727.

The object of the invention is generally to improve and simplify the construction of the 15 mold and to provide improved means for locking the inner and outer shells of the mold in assembled position.

Further objects and advantages will appear in the following description, it being 20 understood that various changes in form, proportions and minor details of construction may be resorted to within the scope of the appended claims.

In the accompanying drawings forming a 25 part of this specification:—Figure 1 is a longitudinal sectional view of a tile mold constructed in accordance with my invention. Fig. 2 is a transverse sectional view. Fig. 3 is a side elevation of a portion of the 30 outer shell. Fig. 4 is a similar view of the tamping member.

Similar numerals of reference indicate corresponding parts in all of the figures of the drawings.

35 The improved mold forming the subject matter of the present invention includes an inner shell 5, and an outer shell 6, said shells being spaced apart by a pallet 7 to form an intermediate molding compartment 8. The pallet 7 is provided with a depending rib or flange 9 which rests on a platform or support 10 so that the operator may readily grasp the edge of said pallet when lifting the pipe or tile. The outer shell 6 is preferably 40 formed in two sections, pivotally connected at 11 thereby to permit said sections to be swung laterally to open and closed positions.

45 As a means for locking the pivoted sections of the outer shell in closed position, one of said shell sections is provided with spaced brackets 12 having perforated ears 13 formed integral therewith and provided with laterally extending guide fingers 14 arranged to embrace the upper and lower

edges of corresponding brackets 15 carried 55 by the mating shell section.

Slidably mounted in the perforations of the ears 13 is a vertically movable rod 16 carrying spaced hooks 17, the latter being provided with inclined or cam faces 18 arranged to bear against the correspondingly inclined faces of lugs or projections 19 extending laterally from the brackets 15, as shown.

The hooks 17 are provided with sockets 65 for the reception of the rod 16, said hooks being locked in adjusted position by means of clamping screws 20 extending through the sockets of the hooks and bearing against the rod 16. 70

Slidably mounted on the rod 16 beneath the upper hook 17 is a sleeve or collar 21 to which is pivotally connected one end of a link 22, the opposite end of the link being pivotally connected at 23 with an operating 75 lever 24.

The operating lever 24 is pivotally mounted on a bracket, or support 25 carried by one of the outer shell sections so that when the free end of said lever is moved upwardly 80 the link 22 will exert a vertical pull on the rod 16 and thus cause the cam faces of the hooks 17 to engage the adjacent lugs or projections 19 and lock the abutting ends of the outer shell section in assembled position. 85

It is obvious that when the lever 24 is moved in the opposite direction, the hooks 17 will be disengaged from the projections 19, thereby to permit the outer shell sections to be swung laterally to open position. 90

The sleeve 21 is adjustable vertically of the rod 16 so as to vary the throw or movement of the hooks 17, said sleeve being locked in adjusted position by a clamping screw 26. 95

The locking mechanism for the inner shell comprises spaced horizontally disposed brackets 27 secured to the adjacent ends of said inner shell and is provided with lugs or projections 28 having oppositely disposed 100 inclined faces 29 and 30.

Arranged at the rear of the over-lapping edges 31 of the inner shell is an operating rod 32 provided with oppositely disposed wedge shaped heads 33, the inclined faces 105 of which bear against the adjacent inclined faces 30 of the lugs 28 and serve to force the over-lapping edges 31 of the shell apart

when the rod 32 is moved in one direction, thereby to expand said inner shell and force the latter into engagement with the inner rim of the pallet 7.

5 The heads 33 are threaded on the rod 32 and are each provided at their reduced end with oppositely disposed hooks 34 having inclined or cam faces 35 for engagement with the inclined faces 29 of the adjacent 10 lugs 28 so that on the reverse movement of the rod 32 the inclined faces of the hook 34 will engage the lugs 28 and draw the overlapping ends 31 of the inner shell together so as to permit the ready removal of said 15 inner shell from the interior of the molded pipe or tile.

A collar 35', similar in construction to the collar 21 is mounted for vertical movement on the rod 32 and connected through the 20 medium of a link 36 with an operating lever 37. It will thus be seen that when the lever 37 is swung downwardly to the position shown in Fig. 1 of the drawings, the wedge shaped heads 31 will expand the inner shell 25 and cause the latter firmly to engage the pallet 7, and when said lever is moved in the direction of the top of the mold the hooks 34 by engagement with the lugs 28 will draw the ends of the inner shell together so as 30 to permit the removal of said inner shell.

The opposite ends of the inner shell are preferably reinforced and strengthened by the provision of metallic bands or hoops 38, there being T shaped reinforcing bands 39 35 secured to the upper edge of the outer shell for a similar purpose.

Associated with the mold is a conical shaped cap or cover 40 provided with a marginal flange 41, which rests on the upper 40 reinforcing band 38 of the inner shell, said cap serving to direct the concrete or other material to the molding compartment 8 when filling the latter.

In operation the pallet 7 is placed in position 45 on the platform 10 and the inner shell clamped in engagement with the inner periphery of the pallet by pressing downwardly on the operating lever 37. The outer shell is then positioned on the support 50 10 and the lever 24 actuated to clamp the pivoted sections of said outer shell in engagement with the outer periphery of the pallet. The parts being thus arranged in assembled position the cap or cover is placed 55 on the reinforcing band of the inner shell and the cement, or concrete shoveled into

the molding compartment and tamped with the tool indicated at 42, in Fig. 4 of the drawings.

After the tile is formed the lever 24 is 60 actuated to release the outer shell, and the lever 37 moved upwardly in the direction of the top of the mold so as to contract the inner shell, thereby permitting both shells to be removed from the molded product, which 65 latter may be carried on the pallet 7 to the drying racks and allowed to stand until sufficiently hard for use.

The cover 40 not only serves to direct the material into the molding compartment, but 70 also forms a housing for the interior of the inner shell when filling the mold.

Having thus described the invention what is claimed is:—

1. A mold including an inner expandible 75 shell and an outer sectional shell, spaced apart to form an intermediate molding compartment, headed lugs secured to the adjacent ends of the inner shell, a rod having oppositely disposed wedge shaped heads operating between the adjacent lugs for expanding the inner shell, and hooks carried by and having their free ends spaced from said heads and also arranged to engage the lugs for contracting said inner shell, the said 80 hooks and wedge-shaped heads engaging under the heads of the lugs.

2. A mold including an inner shell, a sectional outer shell spaced from the inner shell to form an intermediate molding compartment, brackets secured to one of the sections of the outer shell and provided with laterally extending lugs, perforated brackets secured to the mating section and provided with guide fingers arranged to embrace the 90 brackets of the mating section, a rod slidably mounted in the perforations of the ears, hooks extending upwardly in the same direction from the rod and provided with cam faces arranged to engage the lugs on the adjacent brackets for locking the sections of the outer shell in assembled position, an operating lever, and a link connection between the operating lever and said rod.

In testimony that I claim the foregoing as 105 my own, I have hereto affixed my signature in the presence of two witnesses.

FRANCIS M. WILTROUT.
